UNITED STATES PATENT OFFICE.

ABRAHAM L. SPRAGUE, OF MILTON, MASSACHUSETTS, ASSIGNOR TO SPRAGUE CAR APPLIANCE COMPANY, OF PORTLAND, MAINE, A CORPORATION OF MAINE.

CAR-TRACK-SANDING DEVICE.

SPECIFICATION forming part of Letters Patent No. 692,938, dated February 11, 1902.

Application filed July 12, 1901. Serial No. 67,973. (No model.)

To all whom it may concern:

Be it known that I, ABRAHAM L. SPRAGUE, a citizen of the United States, residing at Milton, in the county of Norfolk and State of Massachusetts, have invented new and useful Improvements in Car-Track-Sanding Devices, of which the following is a specification.

This invention relates to improvements in car-track-sanding devices adapted for use on tramway or motor cars for the purpose of sanding the rail or rails when slippery or when going up grades, as will hereinafter be more fully shown and described, reference being had to the accompanying drawings, wherein—

15 Figure 1 represents a top plan view of the invention as applied to a tram or motor car. Fig. 2 represents a partial side elevation of a car provided with my improved car-track-sanding device. Fig. 3 represents a detail 20 side elevation of the mechanism for operating the rotary cylinder of the sanding device, showing said mechanism in its normal position. Fig. 4 represents a similar view showing said mechanism in operative position.

25 Fig. 5 represents a cross-section on the line 5 5, shown in Fig. 3. Fig. 6 represents a detail exterior end view of the head attached to one end of the rotary sand-receptacle. Fig. 7 represents an interior end view of Fig. 6.

30 Fig. 8 represents a side view of Fig. 6. Fig. 9 represents a cross-section on the line 9 9, shown in Fig. 8. Fig. 10 represents a cross-section on the line 10 10, shown in Fig. 8. Fig. 11 represents a detail top plan view of 35 the sanding device, parts being shown in section. Fig. 12 represents an end elevation as seen from X in Fig. 11. Fig. 13 represents an interior end view of the stationary hood or cover into which the sand is conveyed from

40 the rotary receptacle during the rotation of the latter. Fig. 14 represents a vertical section on the line 14 14, shown in Fig. 13. Fig. 15 represents a central longitudinal section on the line 15 15, shown in Fig. 12; and Fig. 45 16 represents an exterior end view of the stationary hood or cover.

Similar letters refer to similar parts wherever they occur on the different parts of the drawings.

50 A in Figs. 1 and 2 represents the car-frame,

B the floor, of which B' is one of the end platforms, and C the dasher, as is common in electric or other motor cars. E E represent the wheels at one end of the car, said wheels being secured to the axle F, which is suitably 55 journaled in bearings beneath the car-frame, as usual. G G are the rails of the car-track.

The improved track-sanding device is composed of an intermittently rotary preferably cylindrical sand-receptacle H, having secured 60 to its inner end or cast integral therewith a solid end piece H', in one piece with which is preferably made the central shaft or trunnion h, journaled in a bearing-bracket I, secured in a suitable manner to the cross-bar or pilot- 65 board A' or other portion of the car-frame, as may be most practical.

Preferably integral with the end portion H' of the sand-receptacle H is a ratchet-wheel h'. (Shown in Figs. 3, 4, 11, 12, and 15.) On 70 the trunnion or spindle h is pivoted a lever K, and to the latter is pivoted at l a pawl L, that engages the ratchet-wheel h', as shown in Figs. 3, 4, 11, 12, and 15.

Preferably in one piece with the bracket I 75 is made an arm or projection I', which is connected by means of a preferably-coiled spring I" to the lever K, as shown in Figs. 3, 4, and 12.

I³ is a stop projection on the bracket I, which serves as a stop for limiting the back- 80 ward motion of the lever K when released.

M is a second pawl pivoted at m to the bracket I, which pawl is held in engagement with the ratchet-wheel h' either by gravity or spring-pressure, and it serves the purpose of 85 holding the said ratchet-wheel h' and the sand-receptacle connected to it in a stationary position during the backward motion of the lever K and pawl L, as represented in Figs. 3, 4, and 12. For the purpose of intermittently 90 rotating the said receptacle H from time to time, as needed to discharge a quantity of sand on the rail in front of the wheel or wheels, I preferably make use of a pedal-actuated mechanism, (shown in Figs. 3 and 4,) which 95 is constructed as follows:

To the under side of the platform B' is secured a bracket N, to which is pivoted at n a knee or bell-crank lever N' N'', which is normally held in the position shown in Fig. 3 by 100

the influence of a spring O, secured in one end to the bell-crank portion N" and in the other end preferably to an extension N³ on the lower portion of the bracket N, as shown in Figs. 3 and 4.

P is a pedal preferably guided in a bushing b in the platform B', as shown in Figs. 3, 4, and 5. The lower end of said pedal is preferably forked, as shown in Fig. 5, and is supported upon the bell-crank portion N', as shown in Figs. 3, 4, and 5. When the motor-man depresses the pedal P, it causes the bell-crank N' N" to assume the position shown in Fig. 4.

15 To the upper end of the lever K is pivotally connected a metal rod or link Q, the forward end of which is provided on its upper side with a toothed or serrated rack q, (shown in Figs. 1, 2, 3, and 4,) and said serrated portion 20 of the said link or rod Q is loosely guided in the lower end of the bell-crank portion N", as shown in Figs. 3 and 4. To the bell-crank portion N" is pivoted or hung at n⁴ a pawl N⁴, which is provided with an upwardly-projecting hook N⁵, adapted to rest upon a tooth or projection n⁵ on the lower end of the bracket N when the bell-crank lever N' N" is in its normal position, (shown in Fig. 3,) and when in such position the pawl N⁴ is held raised out 25 of engagement with the rack q, as represented in Fig. 3. When the pedal P is depressed it causes the bell-crank lever N' N" to turn from the position shown in Fig. 3 to that shown in Fig. 4, and during the first portion of such 30 rocking motion of said bell-crank lever the hook N⁵ is disengaged from the tooth n⁵, causing the pawl N⁴ to drop by gravity into engagement with the rack q, whereby the rod Q is caused to be moved in the direction of the 35 arrow shown in Fig. 3 to the position shown in Fig. 4, thereby causing the sand receptacle or drum H to be turned a partial revolution around its axis by the engagement of the pawl L with the ratchet-wheel h' on said sand-receptacle, from which a proper quantity of sand is 40 then discharged, as will hereinafter be described. When the operator relieves his foot-pressure from the pedal P, the knee-lever N' N" will automatically be returned to the position shown in Fig. 3 by the influence of the 45 spring O, and during such movement the pawl N⁴ will be automatically raised out of engagement with the rack q by the pawl-hook N⁵ engaging the projection n⁵ in the lower end 50 of the bracket N, as shown in Fig. 3, and during such release of the link Q its lever K is automatically swung from the position shown in Fig. 4 to that shown in Fig. 3 by the influence of the spring I", in which position the sand-receptacle is held stationary 55 until the pedal P is again depressed for intermittently rotating the sand-receptacle for discharging therefrom a proper and desired quantity of sand.

60 65 The sand-distributing device used in connection with the intermittently rotary sand receptacle or cylinder H is constructed as fol-

lows: Within one end of said cylinder H is secured in a suitable manner a preferably cast-iron head or diaphragm R, provided with a series of peripheral ports r r. Integral with said head R are cast a series of internal receiving and external delivery buckets R' and R", which are in communication with each other by means of the ports r r, as shown in Figs. 8, 11, and 15. Integral with the head R and external buckets R" is cast an annular ring R². To the said head R is secured or made integral with it a spindle or axle R⁴, which is journaled in a bearing-bracket S, secured to the cross-bar or pilot-board A', as shown in Figs. 1, 2, 11, 15, and 16. Attached to the bracket S is a preferably conical hood T, provided at its under side with a delivery-spout T', from which the sand drops onto the rail in front of the car-wheel during the intermittent rotary motion of the sand-receptacle H. To the interior of said hood T is secured a tapering chute T", open from top to bottom, as shown in Figs 13, 14, 15, and 16, which serves to receive the sand from the buckets R" and to convey it to the said chute T", from which it is caused to drop through the spout T' onto the rail in front of the wheel. During the rotation of the sand-receptacle H the sand contained therein is carried by the internal buckets R' and conveyed through the ports r into the outer buckets R" and discharged therefrom through the inner open ends r" of said buckets R" into the chute T", and through the spout or discharge-opening T', as above described. The front edge r' of the inner buckets R' projects slightly in advance of the edge r³ of the port r in the head R for the purpose of covering or overlapping the space behind such port, thereby preventing the sand from escaping through said port from the sand-receptacle after the sand has been discharged through the outer buckets R". The inner buckets R' serve the purpose of feeding the sand through the port-holes r into the outer buckets R", from which it drops into the chute T" and through the spout T' onto the rail when any one of the outer buckets R" reaches its highest position during the intermittent rotary motion of the sand-receptacle.

From the above it will be seen that the desired quantity of sand may be discharged onto the rail in front of the wheel simply by depressing the pedal P one or more times, causing the sand-receptacle H to be intermittently rotated and causing the inner buckets R' to feed the sand through the ports r and conduct a portion of the sand into the outer buckets R", from which it is delivered into the chute T" and conducted through the spout T' onto the rail.

H" is a removable cover on the sand-receptacle H, covering and opening in the same, through which said receptacle may be charged with sand from time to time, as needed.

It will be noticed that this, my improved sanding device, is entirely devoid of any

valves, shutters, or intermittently-actuated opening or closing devices liable to become clogged and obstructed, my device being provided with a series of internal and external buckets connected by ports through a head, by which ports a communication is established between the said inner and outer buckets, the inner buckets preventing the sand from escaping through said port-holes after the inner and outer buckets have reached or passed their highest position during their rotation.

Having thus fully described the nature, construction, and operation of my invention, I wish to secure by Letters Patent and claim—

1. The herein-described car-track-sanding device consisting of an intermittently-actuated rotary sand-receptacle H having internal and external buckets secured within one end of said receptacle, ports connecting said internal and external buckets, a stationary hood arranged adjacent to said buckets, a chute within said hood and a discharge opening or spout leading from the said hood substantially as and for the purpose set forth.

2. The herein-described car-track-sanding device consisting of an intermittently-actuated rotary sand-receptacle having internal and external buckets connected by ports, a stationary hood containing a chute and discharge spout or opening and intermediate connecting mechanism to a pedal for impart-

ing an intermittent rotary motion to said sand-receptacle, substantially as and for the purpose set forth.

35

3. In a car-track-sanding device, an intermittently rotary sand-receptacle H having in one of its ends a head R provided with peripheral ports r, internal and external buckets R' and R" each of the former having its forward edge r' projecting slightly in advance of the forward edge r³ of the port r for the purpose herein set forth and described.

4. In a car-track-sanding device an intermittently-actuated rotary sand-receptacle having attached to it a ratchet-wheel actuated by a rocking pawl-carrying lever, combined with a link or rod Q connected to said lever and having a rack q in its forward end, a bracket N secured to the forward portion of the car, a bell-crank lever pivoted to said bracket, a pedal for actuating said bell-crank lever, and a pawl N⁴ pivoted to said bell-crank lever for engagement with said rack during the depression of the said pedal substantially as and for the purpose set forth.

In testimony whereof I have hereunto set my hand in presence of two subscribing witnesses.

ABRAHAM L. SPRAGUE.
